[57] CLAIM

The ornamental design for a chime housing, as shown and described.

DESCRIPTION

FIG. 1 is a perspective view of a chime housing illustrating my new design.

FIG. 2 is a front elevational view of the chime housing of FIG. 1.

FIG. 3 is an enlarged rear elevational view of the chime housing of FIG. 1;

FIG. 4 is a horizontal sectional view of the housing of FIG. 1 taken along the line 4—4 of FIG. 3.

FIG. 5 is an enlarged side elevational view of the chime housing of FIG. 1;

FIG. 6 is a vertical sectional view of the housing of FIG. 3 taken along the line of 6—6 of FIG. 3.

FIG. 7 is an enlarged top plan view of the chime housing of FIG. 1;

FIG. 8 is an enlarged bottom plan view of the chime housing shown in FIG. 1.

The wickerwork in FIGS. 1 and 2 and fabric cross-hatching in FIG. 3 are partially shown for convenience of illustration, it being understood that they are continuous over the areas indicated.
